UNITED STATES PATENT OFFICE.

RUPERT NELSON, OF SAN FRANCISCO, CALIFORNIA.

METHOD OF AND APPARATUS FOR DETECTING THE PRESENCE OF ORE DEPOSITS IN THE EARTH.

1,248,380.

Specification of Letters Patent.

Patented Nov. 27, 1917.

Application filed April 3, 1915. Serial No. 18,973.

To all whom it may concern:

Be it known that I, RUPERT NELSON, a subject of the King of Sweden, residing at 1356 Eighth avenue, San Francisco, in the county of San Francisco and State of California, have invented new and useful Improvements in Methods of and Apparatus for Detecting the Presence of Ore Deposits in the Earth, of which the following is a specification.

This invention relates to the method of and apparatus for detecting the presence of ore in the earth and has for its primary object the provision of a structure wherein 15 different metals can be substituted for the electrode that is inserted into the earth so as to tell whether the ore is positively or negatively electrified with relation to the electrode, thus determining into what class 20 the ore belongs.

The invention consists in the features of construction, combination, and arrangement of parts, hereinafter fully described and claimed, reference being had to the accompanying drawings, in which:

The figure is a diagrammatic view illustrating the application of the device.

In the drawing, the numeral 1 designates a quadrant type of electrometer, the quadrants of which are electrically connected by way of conductors 2 and 3 to a source of current 4. The diametrically opposite quadrants are connected to opposite sides of the battery so as to be electrified, negatively 25 and positively respectively.

5 indicates a pointed electrode adapted to be inserted into the earth and as shown has its upper extremity provided with a binding post 6 whereby the electrode may be 0 electrically connected to the needle 7 of the electrometer by means of the conductor 8.

In the application of the device, the electrode is forced into the surface of the earth, whereupon the needle will receive an excess 5 of either negative or positive electrification, according to whether the ore is electrified positively or negatively with relation to the electrode. If the ore should be positively electrified with relation to the electrode 5, the needle would be negatively electrified and moved under the positive quadrant, this action being increased by the repulsion of the negatively electrified quadrant. To determine the relation of the electrification of the ore with relation to the electrode, I sub-

stitute different metals for the electrode and notice the deflection of the needle of the electrometer, thus giving visual indications as to the relation of the electrification of the ore to the metal forming the electrode, it 60 being well known that a metal acts positive with relation to one metal while it will act negative with relation to another metal.

Attention is directed to the fact that, in my device, when the ore is located near the 65 surface of the earth, the action of the electrometer will be oscillatory whereas the greater the depth of the metal, the greater is the retardation of the action of the electrometer.

Having described my invention, what I 70 claim is:

1. The method of locating and ascertaining the character of ore bodies which consists in inserting into the ground an electrode, connecting the electrode to an electrometer, noting the deflection of the needle, substituting an electrode of a different material, and comparing the deflection obtained in the second instance with the deflection obtained 75 in the first instance.

2. The method of locating and ascertaining the character of ore bodies which consists in inserting into the ground an electrode of a metallic material, connecting the 80 electrode to an electrometer, noting the deflection of the needle, substituting an electrode of a different metallic material, and comparing the deflection obtained in the second instance with the deflection obtained 85 in the first instance.

3. The method of locating and determining the character of ore bodies which consists in inserting into the ground an electrode of some metallic material, connecting 90 the electrode to the vane of a quadrant electrometer, the sectors of which are charged alternately positively and negatively, noting the deflection of the needle, substituting an electrode of a different metallic material and 100 comparing the deflection obtained in the second instance with the deflection obtained in the first instance.

In testimony whereof I affix my signature in presence of two witnesses.

RUPERT NELSON.
